Primary Examiner — Ian Simmons*Assistant Examiner* — Shannon Morgan(74) *Attorney, Agent, or Firm* — Gary E. Lambert; David J. Connaughton, Jr.; Lambert & Associates(57) **CLAIM**

The ornamental design for a cloth holder, as shown and described.

DESCRIPTION

FIG. 1 is a front elevational view of a cloth holder showing my new design;

FIG. 2 is a side elevational view thereof;

FIG. 3 is a bottom plan view thereof;

(Continued)

FIG. 4 is a top plan view thereof; and,
 FIG. 5 is a front, side perspective view of the cloth holder
 in FIG. 1 showing my new design.
 The broken lines shown in FIG. 5 of the cloth holder are for
 the purposes of illustrating environment, and form no part of
 the claimed design.

1 Claim, 2 Drawing Sheets
